MARINE FLOAT

Samuel S. Amato, Philadelphia, Pa.

Application March 27, 1945, Serial No. 585,023

8 Claims. (Cl. 114—16.7)

1

This invention relates to marine floats, and particularly to compartment or chamber floats, to be carried by a vessel or carrier, such as a submarine boat or surface ship, for conducting crew members or passengers from the carrier, especially in times of stress in an effort to escape.

The device is operable for relatively different purposes under various conditions, such as acting as mere transport means from a carrier when the carrier is not damaged or in danger, or as a completely enclosed life boat for entry thereto from a sheltered deck or compartment of a surface ship. However, the purpose of the invention, as particularly illustrated herein, is as escape means for the crew of a disabled submarine beneath the water surface.

An object of the invention is to facilitate the rapid boarding, sealing and release of a float of the indicated character, and to guard the same against leakage at the hatchway means, and fouling of the float irrespective of any of a wide range of angles from its normal position that the float may have at the time of its release.

Another object is to not only facilitate the release of the float and to effect the other advantages stated, but also to facilitate the sealing of the carrier compartment from which the float is released, under safe or usual conditions, or where the carrier, although flooded at other parts, may still have parts which may be saved by such sealing.

Another object is to brace the float relative to the carrier in substantially all directions, and against severe shocks as in crash diving of the carrier.

Another object is to attach the float to, and to support the same on, a carrier by apparatus including yieldable means providing binding action in effecting the attachment and tending to force the float away from the carrier when the attachment is released.

Another object is to ensure the ready manual operation from opposite sides of any or all hatch closure means associated with the apparatus, whereby the closure means is watertight and cannot inadvertently be locked closed from either side such that it cannot be readily opened from the other side, and by which, after release of the float and arrival at the water surface, the exit hatch may be opened from within or, as in case of disability of persons in the float, may be opened by others from the outer side.

Another object is to ensure the opposite-side hatch locking and releasing means against accidental opening either by persons associated

5

therewith or from floating objects, but which, when so intended, may be closed and locked, and unlocked and released by substantially the quickest and easiest manual or hand operation.

With such objects in view, as well as other advantages which may be incident to a utilization of the improvement, the invention comprises the parts and combinations thereof hereinafter set forth and claimed, with the understanding that the several necessary elements constituting the same may be varied in proportion, arrangement and texture without departing from the spirit and scope of the invention.

In order to make the invention more clearly understood, means are shown in the accompanying drawings for carrying the invention into practical effect, without limiting the improvements to the useful applications thereof to the particular constructions which, for purposes of explanation, are made the subject of illustration.

20 In the drawings:

Figure 1 is a view, partially in side elevation and partially in section, of a marine float embodying the invention, together with a portion of a carrier structure, such as a submarine deck, on which the float is mounted.

Figure 2 is a view, in end elevation, of the parts of Figure 1 which are located above deck.

Figure 3 is a bottom plan view, on a reduced scale, of the main float body, as it appears when released from the carrier.

Figure 4 is a bottom plan view of the lower central portion of the apparatus shown in Figure 1.

Figure 5 is a sectional side view of a modified form of hatch closure lock.

Figure 6 is a view taken substantially along the line 6—6 of Figure 5.

Referring particularly to Figure 1, the device 40 comprises, in general, hatchway means 10 for releasably attaching a hollow float structure 12 to a carrier deck or other support 14, cradles 16 secured to the deck 14, and yieldable means 18 on the cradles 16.

45 The hatchway means 10 comprises a manhole member 20, sealed and secured to the deck 14, and having a top flange 22 on the deck, and an exteriorly screw threaded depending tubular portion 24.

50 The hatchway means 10 further comprises an interiorly threaded manhole nut 26 on the portion 24 having, in this instance, two radially oppositely extending handles 28, and normally surrounding the outer threads of an exteriorly and interiorly threaded manhole body 30 having, in

this instance, two pairs of radially oppositely extending handles 31 at right angles to each other.

The hatchway means further comprises an interiorly threaded manhole element 32 sealed and secured to the float 12 around a manhole opening therein and having a flange 34 for compressing a sealing gasket 36 between the deck manhole member 20 and the float manhole element 32.

The hatchway means further comprises an exteriorly threaded hatchway device or tube 38 normally extending through the float manhole element 32 in threaded cooperation therewith to a position below the deck or boat manhole member 20 into the manhole body 30 in threaded cooperation therewith, and having a fixed shoulder 40 for compressing a sealing gasket 42 against the float manhole element 32. A binding gasket 44 may also be provided between the manhole body 30 and the tubular portion 24 of the deck manhole member 20. The hatchway device 38 has, in this instance, a halved ring 46 secured to the shoulder 40 thereabout and provided with three symmetrically spaced upwardly extending handles 48. The device 38 has a companion ladder 50, and a hinge mounting 52, the latter of which is adapted to support a hatch closure or entrance door 54, as by a pin 56.

The door 54 has a channel shaped rim 58 containing a yieldable body 60 of rubber or the like for fitting over and about the top edge of the hatchway tube or device 38, when the door is closed, as shown, and a counterbalance element or weight 62 to render it easy to open and close the door.

The door 54, in this instance, is further provided with a bearing portion 64 containing packing means 66 and a packing gland 68, through all of which a turnable shaft 70 extends. A lock member 72, fixed to the shaft 70 at the outer, or under, side of the door, is adapted to cooperate with a lock member 74 fixed to the device 38. A handle 76 is fixed to the lock member 72, and thereby to the shaft 70 at the outer side of the door 54, and a handle 78, having a fixed inner end member 80, is fixed to the shaft 70 at the inner side of the door 54 relative to the float 12.

The manhole body 30 is provided with an entrance door 82 similar to the door 54 and similarly provided with a counterbalance element 62, a bearing portion 64, packing means 66, a packing gland 68, a shaft 70, lock members 72 and 74, a pin 56, handles 76 and 78, a rim 58 and a yieldable body 60 fitting an edge 84 of the body 30.

The float 12 has an exit door or cover 86 similar to, but in this instance, larger than the doors 54 and 82, and similarly provided with the other identified elements, except the counterbalance element 62 which, however, may be provided in this instance also.

Referring to Figures 1, 2 and 3, the float structure 12 comprises a shell, as of stainless sheet steel or other material, having a cylindrical body 88, rounded or dome-like end bells or members 90, a floor 92, reinforcing inner structure 94, and handrail means 96.

As better seen in Figures 1 and 2, the cradles 16, indicated in this instance as of cast metal, are disposed at the opposite ends of the float body 88 adjacent to lines 98 of joinder thereof to the end bells 90. Each cradle 16 comprises a main body web 100 having sea-wash or lightening holes 102, ribbed uprights 104, lateral braces 106, a bottom web 108 and a top edge 110 of the web 100 which, although it is contoured to the cylindrical lines of the float, does not normally touch the float, 75

but provides a space 112 between the web and the float.

Refer particularly to the right hand side of Figure 2, showing the yieldable means 18, which at this place is typical of each of the three means 18 on each cradle 16.

Each means 18 comprises, as an illustration, a bracket or support 114, with the bracket or support of the lower central means 18 on the bottom web 108, and the bracket or support 114 of each higher means 18 on the web 100. Each bracket or support has an integral cup 116 which is vented, as by a hole 118, and is telescoped by a cap 120 having a shoe 122 contoured to the float surface engaged thereby or which surface may be contoured to the shoe. A spring 124 in the cup 116 urges the cap 120 outwardly, and a lubricating medium may be provided in the cup 116 and between the latter and the cap 120.

Referring to Figures 1 and 3, the float manhole element 32 of the hatchway means 18 is provided with means, lending rigidity to the float over the bottom surface thereof, in the form of legs 126, which are, in this case, integral with the element 32 and emanate therefrom lengthwise, laterally and upwardly on the cylindrical surface of the shell body 88 to ends 128 very closely approaching the web 100 for longitudinal bracing thereby.

Since a purpose hereof is to avoid as much as possible any interference from having the float break free, upper edges 130 of the web 100 so recede or diverge from the edge 110, as continuations thereof, as to provide for a rolling action of the float out of the cradle, under the urge of the springs 124, when the float, at the time of release, may be at an extreme angle to its normal position.

In operation, if closed at the time, the bottom door 82 may easily be released by turning the lower handle 78 to release the lock member 72 from the lock member 74, and the door opened with the assistance of the counterbalance element 62 to prevent sudden falling of the door. With this door opened, it is then only necessary to climb the ladder 50 and to similarly release and open the door 54, with the counterbalance element 62, in this instance, assisting the lift.

Since the lower door 82 is counterbalanced, and requires only a simple turning of the handle 76, the last person leaving the carrier can, without undue trouble or loss of time, close the door 82.

After all have escaped to the float, the door 54 is as readily closed as it was opened, whereby to establish a water tight seal at the door, whereupon the handles 48 may be manipulated to turn the hatchway device 38 out of the manhole body member 30 to release the float. Upon such release, and very slight lift or movement of the float from the deck 14, the device 38 is immediately returned to its initial position with the shoulder 40 engaging and compressing the gasket 42 against the top of the manhole element 32. With the screw threads on the device 38 comparatively quick and fitted closely with the cooperating threads on the element 32 there will be comparatively little chance for water to enter the float, which contingency may be further guarded against, and the operation facilitated, by lubrication between the threads, or by other means.

Upon release of the float as aforesaid, the springs 124 immediately act to push the float out of the cradles 16 and away from the carrier, and since the lower end of the hatchway device, in closed position, protrudes some distance from the bottom of the float, it may be employed as a reciprocating pusher, if necessary, in an endeavor

to free the float from improbable fouling, or to impart motion to the float against other objects.

It is contemplated, of course, that the float may have any of many other forms, such that it may be more on the order of a usual boat, provided with motive and propelling means, oxygen equipment, a permanent store of food and water, a lighting system, portholes, a periscope, medical supplies, hygienic and sanitary means and any or all of several other conveniences or necessities.

It is contemplated also that the floats may be of various sizes to accommodate various numbers of persons and that one or any other number of floats may be placed at appropriate positions on one carrier to better take care of all who may be variously situated according to the location of the float or floats depending on the size of the carrier, the maximum number of persons adapted for carriage and other factors.

Upon rise of the float to the water's surface, the float exit door 86 may be opened from within, as in the cases of the doors 82 and 54, and the occupants leave the float to a rescue means, in this case, by stepping from the floor 92 to the top of the door 54, with the possible assistance of the handrail 96 which is provided for the occupants as bracing means against movements of the float.

The legs 126, in addition to acting as bracing or trussing means for the float at the bottom thereof under normal conditions, also act as a keel or ballast to maintain the float upright.

Referring to Figures 5 and 6, a modification of the door locking and releasing means is shown in connection with a door 134 corresponding to parts of the lower door 82 of Figure 1 and constructed similarly thereto. In this instance a shaft 136, although it may be provided with radial handles similar to the handles 76 and 78, is shown as having handwheels 138 and 140, as well as a worm screw 142 fixed thereto. The screw 142 engages a worm wheel 144 fixed to a shaft 146 journaled in bearings 148 on the door 134, and carrying fixed thereto a bevel gear wheel 150 which engages a similar gear wheel 152. The latter is fixed to a stud shaft 154, journaled in the cover 134, and carrying fixed thereto a lock member 156 similar to the above-indicated lock member 72 and cooperating with a lock member or detent 158 on a member similar to the manhole body 30.

Such means, although as shown being slightly slower in action than the above-described locking and releasing means, is better protected against accidental or inadvertent operation, because, although just as simple in operation, it requires deliberation and may not be simply knocked open or closed with one blow and is not likely to be battered open by floating objects.

The arrangement of the parts of the hatchway means 10 whereby the gaskets 36 and 42 are independently compressed, and the closure means or door 82 is supported through the intermediary of the boat or deck manhole member 20, facilitates construction and assembly, ensures a better seal at both gaskets and has other advantages, since the hatchway device 10 may be secured tightly in place in the manhole element 32 against the gasket 42, before mounting the float on the boat, and the manhole body 30, acting as a nut on the device 10 against the manhole member 20, turned to pull the entire float inwardly, against the action of the yieldable means 18, to compress the gasket 36. The manhole nut 26 operates as a lock nut.

The hatchway device 38 constitutes the sole operative means necessary to release the float, thereby very greatly reducing the time element of release and, since it is of large diameter, it releases the float at once without the danger of binding or locking closed, which might occur where a plurality of smaller attachments are released one at a time and the last one or two attachments are bent or cocked by the eccentric partial release under the buoyancy of the float thus effected.

I claim:

1. In combination, a manhole member for sealed relation to a boat around a manhole thereof and having exterior screw threads, a hollow enclosed float having a manhole opening, an interiorly threaded manhole element sealed to the float around said opening, a sealing gasket between said member and said element, a hatchway device extending through said element in threaded cooperation therewith to a position below said member and having a shoulder over said element, a sealing gasket between said element and said shoulder, an interiorly threaded manhole nut on said member in threaded cooperation therewith, and an interiorly and exteriorly threaded manhole body fitting the exterior threads of said hatchway device and the interior threads of said nut.

2. In combination, a manhole member for sealed relation to a boat around a manhole thereof, a hollow enclosed float having a manhole opening, a manhole element sealed to the float around said opening, in register with said member, sealing means between said member and said element, a hatchway device in said element, sealing means between said element and said device, operating means for rendering said first sealing means effective between said member and said element, and means operating independently of said operating means for rendering said second sealing means effective between said element and said device.

3. In combination, a manhole member for sealed relation to a boat around a manhole thereof and having screw thread means, a hollow enclosed float having a manhole opening, a manhole element sealed to the float around said opening, in register with said member, a hatchway device in said element, closure means for said member, and manhole nut means cooperating with said screw thread means for mounting said closure means relative to said member.

4. In combination, a hollow enclosed float for releasable attachment to a boat, means including a portion on the float and providing a watertight hatchway between the float and the boat, and means emanating from said portion lending rigidity to a substantial portion of the float.

5. In combination, a hollow enclosed float for releasable attachment to a boat, said float including a body portion having a manhole opening, means providing a water-tight hatchway between the float and the boat and including closure means for said opening, and means extending from adjacent to said body portion on the float in reinforcing relation to the float and operating as ballast when the float is released to maintain the float in position with said closure means substantially at the bottom of the float.

6. In combination, a hollow enclosed float for releasable attachment to a boat, means providing a water-tight hatchway between the float and the boat, and having a portion carried by the float

providing an entrance to the float from the boat, and means exteriorly of the float lending rigidity thereto and operating as keel means when the float is released and tending to maintain said entrance at the bottom of the float.

7. In combination, a hollow enclosed float for releasable attachment to a boat, means providing a water-tight hatchway between the float and the boat, means emanating from the boat at opposite sides of said first means each embracing opposite sides of the float above the bottom thereof, and means on the float lending rigidity thereto and extending from said first means substantially to each of said second means.

8. In combination, a hollow enclosed float for releasable attachment to a boat and having inlet and outlet manholes, yieldable means for supporting the float on the boat and bracing the sides of the float above the bottom thereof for free release of the float irrespective of any of a wide range of angles at which the float might be from its normal position, water-tight hatchway means between said inlet manhole and a manhole in the boat and including a single operative means only that is necessary for effective release of the float from the boat under urge from said yieldable means, movable closure means for said holes including means for balancing

5 certain of the closure means, means operable from opposite sides of certain of said closure means for releasably holding the same in closed position, and means emanating from said hatchway means along the bottom of the float for lending rigidity thereto.
